JOURNAL BOX

Donald S. Barrows, Rochester, N. Y., assignor to
The Symington-Gould Corporation, Rochester,
N. Y., a corporation of Maryland

Application December 28, 1934, Serial No. 759,590

10 Claims. (Cl. 308—47)

This invention relates to journal boxes for railway vehicles and, more particularly, to the construction of spring-actuated lids for such boxes.

The principal object of my invention, generally considered, is the provision of an articulated journal box lid comprising a closure member, a hood or spring retainer, a torsion spring and a ball or generally spherical member which serves for connecting the spring and hood to the closure member while allowing for a desired articulation therebetween.

Another object of my invention is the provision of a journal box lid with a hood or spring retainer therefor, said retainer being provided with a pocket having a curved surface normally partially housing the coil portions of the spring and adapted, while the parts are being moved to normal position, to gradually stress or energize said spring to the desired degree.

A further object of my invention is the provision of an articulated journal box lid in which angling or articulation between a hood and closure portion of said lid, as well as necessary movement of the actuating spring is provided by a ball or spherical member normally seated on the front face of the closure member.

Other objects and advantages of the invention relating to the particular arrangement and construction of the various parts will become apparent as the description proceeds.

Referring to the drawing illustrating my invention, the scope whereof is defined by the appended claims:

Figure 1 is a front elevational view of one form of journal box lid embodying my invention.

Fig. 2 is a cross-sectional view on the line 2—2 of Fig. 1, looking in the direction of the arrows, and showing fragmentary portions of an associated journal box.

Referring to the drawing in detail, like parts being designated by like reference characters, there is shown a portion of a journal box 1 provided on its upper surface or roof 2 adjacent the forward or outer edge thereof with a hinge lug 3, which lug is apertured, as indicated at 4, for the passage of a hinge bolt or pintle 5 there-through. Said lug is provided at its front and top with flat faces 6 and 7, respectively, for co-operation with a spring-pressed portion carried

50 by the lid 8 for holding the same in either open or closed position.

The assembled lid 8 comprises a closure member 9 which, in the present embodiment, is shown formed of pressed metal and provided with loops 55 or ears 10 and 11 through which the pintle 5

passes, whereby the same is maintained in hinged relation with respect to the journal box. The apertures through the loops 10 and 11 are desirably elongated transversely with respect to the closure member 9 so as to allow some play to insure the accurate seating of the lid on the box. A spring retainer or hood 12 is formed with co-operating ear or loop portions 13 and 14, also receiving the pintle or hinge pin 5 for pivotally connecting said retainer to the journal box, and also to the closure member 9.

A spring 15 is provided between the retainer or hood 12 and the closure member 9, whereby the same is held in stressed or energized position. Said spring is preferably of the torsion type and comprises a plurality of coiled portions 16 and 17 between which, on a generally straight portion 18 of said spring, is preferably mounted a roller or other antifriction device 19, which engages the hinge lug 3 and alternately presses against the faces 6 and 7 thereof when the lid is in closed and open positions, respectively. The ends of the spring extend downwardly where they are bent toward each other and received in an aperture, receptacle, or sockets in a ball or spherical lid equalizing member 20. The ball 20 is held in position in a pocket 21 in the outer face of the closure member 9 by means of a clip or retainer 22 riveted or otherwise connected to the outer face of said closure member, as indicated at 23, and formed with a spherical portion 24 cooperating with the pocket 21 for housing the lid equalizing ball 20, while allowing equalizing movement thereof. The hood or spring retainer 12 is curved at its lower portion, as indicated at 25, to snugly fit over the clip 22.

In order to maintain the coils 16 and 17 of the spring 15 in proper alignment and provide for energizing said spring, the outer wall of the retainer or hood 12 is desirably formed with a pocket 26 receiving and partially housing the outer portions of said coils, the end walls 27 and 28 defining said pocket being desirably inclined to correspond with the adjacent coils, as illustrated most clearly in Figure 1, and lying closely adjacent to said coils to prevent any material shifting thereof from normal position. On account of the curvature of the wall defining said pocket, said wall serves as a cam for gradually stressing the spring to the desired energized condition during assembly, as will be more fully explained hereinafter.

In order to prevent lifting of the closure member 9 with respect to the hood 12, said hood is desirably formed with an inwardly extending lug 55

or flange 29, which may be part of an angular clip 30, welded or otherwise connected to the inner face of the hood 12, and with its innermost portion received in a corrugation or elongated pocket 31 in the closure member 9 and normally lying closely adjacent and above the ball 20, whereby undesired upward movement of said closure member with respect to said hood is prevented.

10 By reason of the angle which spring 15 makes with the closure member 9, as shown in Fig. 2, there is a vertical force component which tends to lift the closure member vertically with reference to the hood 12, thereby causing the scrolls 15 or ears 11 to bear hard against the underside of the pin 5. By attaching the clip 29 to the hood 12 and causing this to bear against the top of the ball 20, this upward movement of the closure member relative to the hood 12 is prevented, thereby making it easier to operate the lid and relieving the pin of undesired bending strains.

15 The closure member 9 is desirably stiffened by means of corrugations 32 and the pin or pintle 5 may be prevented from undesired loss after 20 application by tabs 33 and 34 which normally overlie the ends thereof and are adapted to be bent to and from retaining positions.

25 A preferred method of assembly of the parts of the articulated lid heretofore described is to 30 first fasten the ball 20 to the front face of the closure member 9 by riveting the clip 22 in place over said ball, said spring 15 being assembled with the ball either before or after this operation by spreading the lower ends until the bent 35 trunnion portions 35 can be slipped into the hole in said ball, when said bent portions will spring together to the position illustrated in Figure 1. The foregoing covers the entire shop assembly operation.

40 For application to the box, the lid with the spring depending therefrom is simply laid in position, said spring swung up until the roller 19 rests against the hinge lug. The separate hood 12 is then dropped over the spring and the holes 45 in its ears 13 and 14 carefully aligned with the lug hole and with the scrolls 10 and 11 on the lid proper. The hinge pin 5 is then passed through the entire series of holes and held in place by the tabs 33 and 34.

50 At this stage, the spring 15 is not under stress, and the hood sticks out at a considerable angle from the lid. Pressure is then applied to the free end 25 of said hood and it is forced down until the coils 16 of the spring snap into the pocket 55 26 in the hood. The spring pressure then holds all parts in final position. To disassemble, it is merely necessary to pry up the lower end 25 of the hood 12 which relieves the spring and allows all the parts to be easily removed.

60 Although a preferred embodiment of my invention has been illustrated, it will be understood that modifications may be made within the spirit and scope of the appended claims.

I claim:

65 1. A journal box lid assembly comprising a closure member formed with a pocket in its outer face, a ball seated in said pocket, a clip riveted to said closure member and nesting over said ball for holding it in place, a spring lying over the face of said closure member and with lower end portions secured to said ball, and a hood covering said spring and held in place thereby.

70 2. A journal box lid assembly comprising a closure member formed with a pocket in its outer face, a ball seated in said pocket, a spring pivot-

ally secured to said ball and comprising a portion formed as a series of coils, and a hood covering said spring and formed with a pocket nesting over said coils, the relation between the coils and the pocketed portion being such that when 5 the hood is in position over said spring it is held in place thereby.

3. A journal box lid assembly comprising a closure member formed with a pocket in its outer face, a ball seated in said pocket, a spring pivotally secured to said ball, a hood covering said spring and formed with an inwardly opening pocket receiving a portion thereof, and a flange extending inwardly from the inner face of said hood, overlying said ball, and with an end portion 15 thereof received in a pocket in the front face of said closure member.

4. A journal box lid assembly comprising a closure member formed with a pocket in its outer face, a ball nesting in said pocket, a spring directly secured to said ball, and a hood covering said spring, said ball being held in place by a separately formed clip detachably secured to said closure member and nesting over said ball, and said hood having its lower portion formed to 25 nest over said clip.

5. In combination, a journal box having a hinge lug, a closure member of a lid assembly pivotally connected thereto, a spring retainer pivotally connected to said lug, a torsion spring positioned between said retainer and closure member and comprising coil portions seated on said retainer and adapted to exert pressure against said lug and lower end portions bent toward one another to form trunnion means, a lid 30 35 equalizing ball connected to said spring, by receiving said trunnion means in an aperture therein, and secured to the front face of said closure member with provision for turning, said retainer having a curved portion which acts as a cam for 40 gradually stressing said spring when said hood is swung about its connection with the lug toward said closure member, said curved portion being so formed that when the spring is stressed to the desired extent, it acts to hold said retainer in 45 normal position with respect to said closure member.

6. A journal box lid assembly comprising a closure member formed with an outwardly opening pocket, a lid equalizing ball seated in said 50 pocket, a ball retainer secured to said closure member and nesting over said ball for holding it in place while allowing free rotation thereof, a spring lying over the face of said closure member and with lower end portions pivotally fitting in 55 a corresponding receptacle in said ball, and a hood covering said spring and ball retainer and pivoted to said closure member.

7. A journal box lid assembly comprising a closure member formed with an outwardly opening pocket, a ball seated in said pocket, a spring with lower end portions bent toward one another and forming journal means on which said ball is adapted to rotate, a hood covering said spring and formed with an inwardly opening pocket 60 65 nestingly receiving a portion thereof, and means extending inwardly from the inner face of said hood and overlying said ball to prevent upward movement thereof.

8. A journal box lid assembly comprising a 70 closure member formed with a pocket in its outer face, a ball seated in said pocket and formed with a receptacle, a spring having lower horizontal trunnion portions pivotally mounted in said receptacle adapted to urge said ball into said pocket, 75

- and a hood covering said spring and formed with an inwardly opening pocket receiving a portion of said spring for holding the closure member assembled therewith.
- 5 9. In combination, a journal box having a hinge lug, a closure member pivotally connected directly thereto, a hood pivotally connected to said lug, a spring having lower horizontal trunnion portions positioned between said hood and closure member, and a ball, with a receptacle in which said trunnion portions are pivoted, seated in a pocket in said closure member, and means for holding said ball in said pocket.
- 10 10. In combination, a journal box having a hinge lug, a lid assembly pivotally connected thereto and comprising a closure member, a hood, a spring, having lower horizontal trunnion portions, positioned between said hood and closure member, and a ball, with a receptacle in which said trunnion portions are pivoted, and free to move with respect to said hood, said closure member having a pocket receiving said ball, and means connected to said closure member for holding 10 said ball in said pocket.

DONALD S. BARROWS.
